CONTAINER OPENER

Richard G. Smythe, New York, N. Y.

Application February 17, 1936, Serial No. 64,315

2 Claims.

(CL. 65—49)

This invention relates to container openers and more particularly to openers for removing stoppers and covers from containers such as bottles, jars, cans and the like.

One of the principal objects of the invention is to provide improved means for removing corks and other types of stoppers from containers of the above-mentioned types of containers.

Another object is to provide a device for removing the cork types of stoppers, which has an increased lifting power over those now known to me. A further object is to provide in the same device an efficient means of unscrewing metallic screw caps from containers, and also means for lifting "pressure-type" caps from food jars such as the "Anchor" type caps. Still another object is to provide a means in the same device for lifting ice cubes and other articles.

The means I prefer to employ for accomplishing the above-mentioned objects, together with other advantageous and novel features of my improved container opener, are illustrated in the drawing accompanying and forming part of this specification, and in which—

Fig. 1 is a front elevation of one form of my improved container opener.

Fig. 2 is a central vertical section of the same taken on the line 2—2 of Fig. 3, and

Fig. 3 is a transverse section of the same taken on the line 3—3 of Fig. 1.

Referring to the drawing, the numeral 2 indicates the frame of the device and said frame has a base portion 3 of annular form adapted to rest on the mouth of a bottle when extracting the stopper therefrom, two upright portions 4, each having a series of teeth 5 formed thereon, and a connecting portion 6 which includes two pairs of pivotal portions 8. There are two slots 9, each of which separates the two pivotal portions of a pair of the same, and said slots serve as working spaces for two gear segments 10, each segment joined to a lever 11 which extends outwardly.

There are two pivot sleeves 12, one for each pair of pivotal portions 8, and two bolts or screws 13, one for each such pivot sleeve 12, said sleeves having collars 14 which are clamped adjacent the outer faces of the rearward pivotal portions of the pairs of the same, while the bolts 13 bear against the washers 15 and these against the forward pivotal portions of said pairs and hold the sleeves fixed so that the respective gear segments can turn thereon, thus permitting their respective levers to turn about the pivot sleeves 12. The washers 15 are preferably interposed between

the collars 14 and the screw heads 16 and the adjacent faces of the pivotal portions 8.

Guide ways 17 preferably having rectilinear surfaces are formed in the frame between the pairs of pivotal portions 8, and slidable to and fro in said ways is a member 18 provided with gear elements such as the circular apertures 19, there being a set of said elements on each side of said member 18 and with which the gear elements 20 of the segments 10 mesh for causing the member 18 to reciprocate when the levers 11 are swung. At the lower part of the member 18 is secured a stopper extracting device 21 preferably helical in form and preferably non-rotary.

Each of the levers 11 has a series of teeth 22 formed opposite the teeth 5 on the frame uprights 4. Outward of the teeth 22 are hooks 23 which are used in removing covers from jars and cans and the operation of which will presently be described. There is a ring 24 which is placed in the aperture 25 of the member 18, which ring acts as a stop to limit the downward movement of the member 18 and also may be used to hang the device to a hook or peg.

The operation of my improved container opener is as follows:

For extracting corks and like stoppers from bottles, the annular base member 3 is placed on and pressed against the bottle mouth and the levers 11 are then pulled by hand outwardly and upwardly, causing the gear segments 10 to move the reciprocating member 18 downward and with it the extracting device 21, down into the cork or stopper. The levers 11 are then moved in the opposite direction, thus pulling the extractor and with it the cork, upward. The pair of levers exerts great force for pulling stoppers, as both hands can be applied to the levers for moving the same.

For removing screw caps from bottles and jars the caps are placed between the set of teeth 5 and the lever teeth 22 and the lever 11 is then pulled toward the frame 2 thus causing the caps to be very tightly held, and the device is then swung so as to unscrew the caps.

"Pressure type" caps are removed by means of the hooks 23. The free end 11a of one of the levers 11 is placed on top of a cap and the hook 23 is placed under the flange or turned under part of the cap and the remainder of the opener is then grasped in the hand and pulled upward, causing the cap to be lifted at one side from the bottle or jar on which it is placed.

The device is used for lifting ice cubes and other articles by placing its annular base portion

3 on top of the cube and closing the lower ends
11a of the levers 11 against the cube and lifting
it as desired. Thus the cubes can be lifted from
one receptacle to another without use of special
5 tongs and without touching them with the hand.

What I claim is:—

1. A container opener comprising a frame
which includes a pair of spaced plates, a portion
10 connecting them midway and having a rectangular
slot extending vertically therethrough, an annular
lower frame part and two struts connecting
the latter to the plates, a member movable
vertically in said slot and fixed against rotation
15 therein, said member having two oppositely dis-
posed sets of spaced annular sockets, a stopper
extractor secured to the lower part of the verti-
cally movable member, two gear segments be-
tween said plates each engaging a set of said
20 sockets, and two levers one on each segment, said
frame and the pairs of spaced plates thereof en-

closing and effective as guards for the movable
gear elements.

2. A container opener comprising a frame
which includes a portion to rest on the mouth of
the container, two spaced plates, portions con-
necting the plates, said portions having rectangu-
lar slots therethrough and two struts connecting
the plates with the first-mentioned portion, two
levers pivoted by said plates, gear elements mov-
able with said levers one set for each lever, a 10
member reciprocative in said slots and fixed
against rotation therein and having spaced aper-
tures oppositely disposed and meshing respective-
ly with the lever gear elements for reciprocating
15 said member, and a stopper extracting means
fixed on the lower part of and movable with the
reciprocative member, said frame and the pairs of
spaced plates thereof enclosing and effective as
guards for the movable gear elements.

RICHARD G. SMYTHE. 20
